UNITED STATES PATENT OFFICE.

CHARLES A. DUNHAM, OF ST. PAUL, MINNESOTA.

ADJUSTABLE DETECTOR-BAR SUPPORT.

1,390,989.

Specification of Letters Patent. Patented Sept. 20, 1921.

Application filed March 25, 1920, Serial No. 368,529. Renewed November 29, 1920. Serial No. 427,204.

To all whom it may concern:

Be it known that I, CHARLES A. DUNHAM, a citizen of the United States, residing at St. Paul, in the county of Ramsey and State 5 of Minnesota, have invented certain new and useful Improvements in Adjustable Detector-Bar Supports, of which the following is a specification.

My invention relates to supports for detector bars used in connection with railway switches, and has for an object the provision 10 of a support which is capable of simultaneous vertical and lateral adjustment.

I will describe one form of detector bar 15 support embodying my invention, and will then point out the novel features thereof in claims.

In the accompanying drawings, Figure 1 is a view showing in front elevation a portion 20 of a railway rail, a portion of a detector bar, and one form of detector bar support embodying my invention. Fig. 2 is a view similar to Fig. 1 but with certain parts removed. Fig. 3 is a sectional view on the 25 line III—III of Fig. 1 looking in the direction of the arrows. Fig. 4 is a view showing in front elevation a block 24 forming part of the support shown in the preceding views. Fig. 5 is a side view of the block 24 shown 30 in Fig. 4.

Similar reference characters refer to similar parts in each of the several views.

Referring first to Figs. 1 and 3, the reference character 14 designates a track rail of 35 a railway track. Located at one side of this rail is a detector bar 8 which is supported on a roller 32 mounted in a bracket 10. This detector bar is provided with a motion plate 7 by virtue of which longitudinal movement 40 of the bar causes the bar to move upwardly beyond the top of a track rail 14.

Located adjacent one of the base flanges of the rail 14 is a member 12, which is attached to the base of the rail in a suitable 45 manner, such, for example, by bolts 16, the ends of which are bent to form hooks 16^a adapted to engage the opposite base flange of the rail. The member 12 is attached to the bolts 16 by means of nuts 16^b. The 50 member 12 is provided with an arm 20 which extends outwardly and downwardly from the member and which is provided with an outer concaved surface having horizontal teeth 22. The reference character 24 55 designates an adjusting block (see Figs. 4 and 5) having an inner convexed surface

provided with teeth 26 arranged to coöperate with the teeth 22 on the arm 20. The outer surface of the block 24 is flat, and is provided with horizontal teeth 28. Extending downwardly from the bracket 10 is a shank 34 provided with teeth 38, which are adapted to coact with the teeth 28 on the outer surface of the block 24. The block 24 is provided with a vertical slot 30 and the shank 34 is provided with a vertical slot 36. A bolt 40 passes through these two slots and through a hole 19 in the arm 20, this bolt being provided with a nut 42 and a suitable nut-locking device 44. It will be seen that by tightening the nut 42 the bracket 10 and the block 24 are rigidly secured to the bracket 12.

It will be observed that the vertical position of the bracket 10, and, consequently, of the detector bar 8 may be varied by moving the bracket 10 upwardly and downwardly on the outer surface of the adjusting block 24, it being necessary only to loosen the nut 42 to accomplish this adjustment. Furthermore, it will be observed that the vertical and lateral position of the bracket 10 and the detector bar 8 with respect to the track rail 14 may be simultaneously varied by moving the block 24 upwardly and downwardly with respect to the member 12, the block 24 and the bracket 10 being retained in fixed relative positions during this adjustment.

The concaved surface on the member 12 and the convexed surface on the block 24 may be so designed that the movement of the block with respect to the member will provide the necessary adjustment to locate the detector bar 8 in the proper position for track rails of various standard shapes and sizes.

Other advantages of a structure embodying my invention are that the design is compact, the necessity for having the adjusting block extend down into the gravel ballast is avoided, and a uniform and continuous bearing is provided on both sides of the adjusting block to insure rigidity of the parts after adjustment.

Although I have herein shown and described only one form of detector bar support embodying my invention, it is understood that various changes and modifications may be made therein within the scope of the appended claims without departing from the spirit and scope of my invention.

Having thus described my invention, what I claim is:

1. A support for a railway detector bar comprising a member fixed to a rail, a block having an inner surface adapted to coöperate with the outer surface of said member for upward and downward movement thereover, one of said surfaces being concaved and the other being convexed, a bracket supported by said block, and means for securing said block to said member in adjusted position.
5
2. A support for a railway detector bar comprising a member fixed to a rail, the outer surface of said member being concaved, a block having a convexed surface adapted to coöperate with said concaved surface for upward and downward movement thereover, a bracket supported by said block, and means for securing said block to said member in adjusted position.
15
3. A support for a railway detector bar comprising a member fixed to a rail, the outer surface of said member being concaved, a block having a convexed surface adapted to coöperate with said concaved surface for upward and downward movement thereover, said block being provided with a vertically-disposed slot, a bracket supported by said block, and a bolt extending through the slot in said block for securing the latter in adjusted position.
25
4. A support for a railway detector bar comprising a member fixed to a rail, the outer surface of said member being concaved, a block having a convexed surface adapted to coöperate with said concaved surface for upward and downward movement thereover, said block being provided with a vertically disposed slot, a bracket having a shank portion in en-

40

gagement with the outer surface of said block, said shank being provided with a vertically-disposed slot, and a bolt extending through both of said slots for securing said block and said shank in adjusted position.
45

5. A support for a railway detector bar comprising a member attached to a track rail and having an outer concaved face, and a detector bar bracket including a part movable therewith and having a convexed surface coöperating with the concaved surface on said member.
50

6. A support for a railway detector bar comprising a member attached to a track rail and having an outer concaved face provided with horizontal teeth, a block having an inner convexed surface provided with teeth coöperating with the teeth on said member, a bracket supported by said block, and means for securing said member, block and bracket together.
55

7. A support for a railway detector bar comprising a member attached to a track rail, a detector bar bracket, and a block interposed between said member and said bracket and having a curved surface coöperating with a curved surface on said member whereby up and down movements of said bracket and said block as a unit will cause simultaneous vertical and lateral adjustment of the bracket with respect to said member.
60
65
70

8. A support for a railway detector bar comprising a member attached to a track rail, a detector bar bracket, and means interposed between said member and said bracket and including two coöperating curved surfaces for permitting simultaneous vertical and lateral adjustment of the bracket with respect to the rail.

In testimony whereof I affix my signature.
CHARLES A. DUNHAM.
